COIN CONVEYING CARD

Robert H. Eaton, El Paso, Tex., assignor of fifteen per cent to Morris A. Galatzan, El Paso, Tex., and twenty-five per cent to Clyde E. Brown and five per cent to Edward A. Schanzle, both of Cincinnati, Ohio

Application January 3, 1940, Serial No. 312,267

3 Claims. (Cl. 229—92.9)

The present invention relates to new and useful improvements in coin carriers and more particularly to a coin conveying card which can be used in the transmission of coins by postal service.

The principal object of the present invention is to provide a coin conveying card which can be used in the transmission of coins by postal service with safety.

Still another important object of the invention is to provide a coin conveying card in which the coins can be sturdily retained while at the same time being visible for the purpose of inspection.

These and various other important objects and advantages of the invention will become apparent to the reader of the following specification.

In the drawings:

Figure 1 represents a top plan view of the complete card.

Fig. 2 is a longitudinal sectional view on the line 2—2 of Fig. 1, showing the flap in open position.

Fig. 3 is a longitudinal sectional view on line 3—3 of Fig. 2.

Fig. 4 is a plan view of the blank after it has been struck.

Fig. 5 is a plan view of the transparent window.

Fig. 6 is a plan view of the adhesive frame member.

Fig. 7 is a plan view showing a card struck out in a somewhat different form.

Fig. 8 is a top plan view of a modified form of card.

Fig. 9 is a view showing the reverse side of the card of Fig. 8.

Fig. 10 is a plan view of the blank.

Fig. 11 is a longitudinal sectional view.

Fig. 12 is a view showing the facing annulus.

Fig. 13 is a longitudinal sectional view on the line 13—13 of Fig. 8.

Fig. 14 is a plan view of the frame structure.

Referring to the drawings wherein like numerals designate like parts, it can be seen that in constructing the card, an elongated sheet 5 is employed and in respect to the line 6 on which the elongated strip 5 will be folded, a circular opening 7 is formed in the strip at one side of said line while the section of the card at the other side of the line 6 is struck out to provide the neck 8 and annulus 9, the annulus 9 having an opening 10 therein approximately the same side as the opening 7. When the section a of the card is folded over onto the section b of the card the opening 10 of the annulus 9 will register with the opening 7.

Before the sections are folded together, the Cellophane window assembly 11 is disposed in

place. This assembly 11 consists of the large circular window 12 which is disposed over the opening 7 and the smaller circular window 13 which is disposed over the opening 10 with the narrow neck 14 connecting these windows. The edge portions of these windows 12 and 13 are formed with small openings 15 so that adhesive from the retaining structure generally referred to by numeral 16 can pass through and engage the strip 5.

This retaining structure consists of the annulus 17 and the annulus 18, these annuli being connected by the narrow 19. One entire surface of this structure 16 is coated with an adhesive 20.

15 The window assembly 11 is first disposed in place after which the retaining structure 16 is disposed over the window assembly with the openings 21 and 22 therein registering with the openings 7 and 10 of the card.

20 The sections a and b of the strip 5 are now folded and adhere together, as shown in Fig. 2. The annulus 9 is capable of being folded outwardly with the window 13 secured in place by the annulus 18.

25 A coin can be inserted between the windows and the annulus 9 redispersed back into the section a where it is secured and the card is ready for mailing.

30 Numeral 24 generally refers to a modification wherein the tongue head 9a is square instead of annular and its opening 10a is likewise formed. Excepting for the difference in shape, the construction is identical.

35 A modified form of the invention is shown in Figs. 8 to 14 inclusive and is generally referred to by numeral 30. As shown in Fig. 13, this card consists of an elongated facing strip 31 and the filler strip 32. The facing strip 31 is bent to define the front face portion and the back face portion, which are denoted by characters 31a and 31b, respectively.

40 As shown in Fig. 10, the bass portion 31b is struck out to form the sight opening 33 over which is disposed the transparent window 34. 45 This window opening 33 is at one side of the fold line 35, while at the other side of the fold line 35 the annulus 36 is struck out and by its neck portion 37 connected to the strip 31 at the fold line 35.

50 Numeral 38 denotes the frame structure which consists of a pair of annular members 39 and 40 joined by the connector 41. The frame 39 is adapted to be interposed between the filler strip 32 and the facing strip portion 31b and to frame the window opening 33, while the frame 40 is dis-

posed over the edge portion of the transparent window 42. The window 42 is disposed over the opening 43 in the annulus 36. Crossed wires 44 span the opening in the frame 40 as clearly shown in Figs. 13 and 14. These wires span the window opening at the inside of the transparent window 42.

For the window opening 33 additional crossed wires 45 are used and have their ends disposed through the filler sheet 32 at the edge portion of the opening 46 through the filler sheet 32. These wires 45 are at the opposite side of the filler sheet 32 from the wires 44 and are directly across the inside of the window 34. The opening 46 through the filler sheet 32 acts as a pocket for the reception of the coins.

It can be seen in Figs. 10 and 14 that the strip 31 and the frame unit 38 can be supplied with adhesive to the extent desired so that the facing strip 31 will adhere to the filler strip 32 while permitting the annulus 36 to swing open as a door to permit coins to be inserted in the pocket 46. Numeral 49 denotes a facing annulus for disposition against the filler strip 32 to cover over the ends of the crossed wires 45, as suggested in Fig. 13.

While the foregoing specification sets forth the invention in specific terms, it is to be understood that numerous changes in the shape, size, and materials may be resorted to without departing from the spirit and scope of the invention as claimed hereinafter.

Having described the invention, what is claimed as new is:

1. A coin carrying structure comprising a card 35 made up of a pair of superimposed plies, a coin

receiving opening in one ply, said opening provided with a window, the other ply being formed with a pocket substantially larger than the opening and circumventing said first opening, and a swingable member of substantially the same size as the pocket and adapted to be swung into the pocket and secured in place to prevent displacement of a coin from the opening.

2. A coin carrying structure comprising a card made up of a pair of superimposed plies, a coin receiving opening in one ply, said opening provided with a window, the other ply being formed with a pocket substantially larger than the opening and circumventing said first opening, and a swingable member of substantially the same size as the pocket and adapted to be swung into the pocket and secured in place to prevent displacement of a coin from the opening, said swingable member being provided with a window corresponding in size to the window of the first opening.

3. A coin carrying structure comprising front and back plies and an intermediate ply, one of the outside plies and the intermediate ply being formed with registering openings, a window for the opening of the outside ply, the opening of the inside ply defining a coin receiving pocket, the other outside ply being formed with a relatively large opening circumventing the first-mentioned opening, and a swingable windowed member adapted to be swung into the large opening and secured in place over the opening of the intermediate ply to prevent displacement of a coin therein.

ROBERT H. EATON.
